DESIGN FOR A SUSPENDER FITTING

Floyd A. Knoll, Buffalo, N. Y., assignor to Condor Products, Inc., Buffalo, N. Y.

Application November 16, 1936, Serial No. 65,941

Term of patent 14 years

To all whom it may concern:

Be it known that I, Floyd A. Knoll, a citizen of the United States, residing at Buffalo, Erie County, State of New York, have invented a new, original, and ornamental Design for Suspender Fittings, of which the following is a specification, reference being had to the accompanying drawing, forming a part thereof.

In said drawing:

Fig. 1 is a perspective view of the outer face of a suspender fitting showing my new design.

Fig. 2 is a perspective view of the rear face of the suspender fitting.

The suspender fitting is characterized by a triangular middle portion which is embossed or extended out of the plane of the edge portions and which has a rounded periphery.

I claim:

The ornamental design for a suspender fitting, as shown and described.

FLOYD A. KNOLL.
